UNITED STATES PATENT OFFICE.

ARTHUR OSBORNE, OF HYDE PARK, ASSIGNOR TO J. G. & J. F. LOW, OF CHELSEA, MASSACHUSETTS.

DESIGN FOR A TILE OR CENTER-PIECE.

SPECIFICATION forming part of Design No. 17,385, dated June 7, 1887.

Application filed May 7, 1887. Serial No. 237,492. Term of patent 3½ years.

To all whom it may concern:

Be it known that I, ARTHUR OSBORNE, of Hyde Park, in the county of Norfolk and State of Massachusetts, a citizen of the United States, 5 have invented and produced a new and original Design for Tiles and Center-Pieces, of which the following is a specification, reference being had to the accompanying photographs in explaining the nature thereof.

10 The design belongs to the class known as "rosette" designs; and it comprises the series of figures A B, arranged in successive order, preferably in eight groups, around a common center. The section A is oval in outline, and

15 is separated into two parts or sections by an oval depression, a, and by the sunken parts a'. The section B is raised from the base, has a line or groove, b, running very nearly centrally and radially therein, and is wider at its

20 outer end than at its juncture with the parts of a'. Its outer end curls outward to a limited extent, and is separate from the sections of A

by the depression or recessed portion b'. These figures may be formed upon a surface which is substantially flat, as represented in the photograph C, or upon a surface that is more round or curved, as represented in the photographs D and E.

I would say that I do not confine myself to the arrangement of eight groups, but may employ any number thereof to constitute the entire design.

Having thus fully described my invention, I claim and desire to secure by Letters Patent of the United States—

The design for a tile or center-piece, as herein described, the same consisting of the raised sections A B, having the shape shown, and arranged about a common center.

ARTHUR OSBORNE.
